UNITED STATES PATENT OFFICE

2,186,414

CINDER PULVERIZER

Charles Gilbert Hawley, Cleveland, Ohio, assignor to Downflow Siphon Company, Cleveland, Ohio, a corporation of Ohio

Application September 7, 1938, Serial No. 228,864

2 Claims. (Cl. 230—97)

This invention relates to a cinder pulverizer similar to that described in my earlier application, Serial No. 57,277, filed January 2, 1936, of which the present application is a continuation in part.

The front end or smoke box of a locomotive boiler receives the gases from the fire box and likewise the burning cinders therefrom. The gases are expelled through the stack by the energy of the steam issuing from the exhaust nozzle and unless means operative to intercept the cinders or to pulverize them be provided, large cinders are thrown out in flaming condition and endanger crops and buildings along the right of way.

The object of this invention is to both intercept and pulverize the cinders and to evacuate them through the stack in the form of particles so minute that they quickly lose heat when thrown into the air and settle as inert dust.

The invention is based upon vortical and centrifugal action and is designed to accomplish the aforesaid object and to accomplish the desired results with a minimum of resistance to the flow of the gases, so that proper fire may be kept going in the locomotive fire box and so that the gases may be discharged by a minimum expenditure of energy. Under the present invention the necessary draft may be maintained while using an exhaust nozzle of greater size than usual and hence by that much reducing the back pressure in the engine cylinders.

The invention will be readily understood upon reference to the drawing that forms part of this specification and in which:

Fig. 1 is a vertical longitudinal section of the front end of a locomotive, embodying this invention.

Fig. 2 is a fragmentary horizontal section 40 thereof substantially upon the irregular line 2—2 of Fig. 1; and

Fig. 3 is a vertical cross section substantially upon the irregular line 3—3 of Fig. 1.

Referring to the drawing, the familiar parts 45 of the locomotive are, the smoke box shell 2, its end 5, the front door or plate 6; also the front flue sheet 9, the flues 8, the dry pipe 10, the superheater 11, the steam pipes 12, 12, and the smoke stack comprising the stack proper 3, and 50 the inside stack or petticoat pipe 4. The exhaust nozzle which is coaxial with the inside stack is marked N and the large open space within the smoke box is marked S.

This invention adds few parts to the foregoing. 55 First to be noted is a smoke box floor portion 17,

which is a cinder deflector, having a slanting rear end 17a and which joins the shell 2. There may be corner pieces 17 to prevent lodgment of cinders in those corners. The floor 17 is of generally segmental cross section and as here shown may be made of cement laid in the bottom of the smoke box.

Next to be noted is that the floor portion 17 contains a cavity or bowl C, which is open at the top; the same surrounding the nozzle N and being substantially coaxial with the nozzle N and the stack 4. As shown, the cavity or bowl C may contain a metal lining or bowl proper C', the bottom of which is sealed by the cement in which it is embedded.

The bowl C' becomes a permanent part of the smoke box and a large opening C'' in the bottom of the bowl permits the exhaust nozzle N to be placed in position and to be removed without disturbing either the bowl C' or the bed of cement 20 in which the bowl is laid.

The space between the floor 17 and the lower end of the inside stack 4 is occupied by a tangentially bladed whirl-promoting tuyère 15. Bolts 18 fasten the base of the tuyère to the 25 top of the metal bowl C' and prevent rotation of the tuyère 15. It is, however, readily removable, as will be pointed out.

The tuyère 15 forms the only passage through which the gases may leave the smoke box and 30 enter the stack 4. It is a whirl-promoting element, comprising the many tangential blades 15a, plus a base ring 16 and plus a top ring 14, the latter containing a central opening of the size of the stack 4. The union joint between 35 the lower end of the stack 4 and the top of the tangentially bladed element is desirably openable and is furnished by an interlocking ring 13 which may slip up and down on the stack portion 4.

Clearly all of the gases emerging from the flues 8 and entering the smoke chamber S must pass through the whirl-promoting tuyère 15 in order to reach the stack. The internal diameter of that tuyère is greater than the diameter of the central hole in the top of the tuyère; in other 45 words, the chamber CC within the tuyère is of greater diameter and the whirling gases tending to bank therein are compelled to escape from the chamber CC by first moving downward into the underlying space or cavity C. From that 50 point and leaving the cinders in violent grinding motion in the space C, the gases depart whirlingly upward along with the jet of steam emerging from the nozzle N.

As stated, the tuyère is rigidly fastened to the 55

floor 17 as by bolts 18. There are no rotating parts.

When the ring 13 is lifted to unlock the tuyère, the latter may be slipped forward, once the bolts 5 18 are removed, and then may be taken bodily out through the end of the smoke box, the door 6 being open at the time.

Most of the cinders which enter the space C are rotated rapidly by the force of the whirling 10 gases and are thus ground into powder which being too light to be centrifugally retained is whirlingly evacuated with the gases.

It appears that in every case the cinder deflecting and directing floor 17 should always be retained and it is to be noted that all sparks and cinders which fall on any part thereof are 15 inevitably swept into the centrally located whirl-promoting tuyère 15. When caught in that tuyère the cinders are certain to be whirled 20 downward into the underlying chamber or grinding bowl.

The advantages further to be named include the capacity of the tuyère to be of any desired 25 and large intake area, even relatively slow rotation of the gases being sufficient to accomplish the segregation of the cinders and their ultimate pulverization and it being very desirable to perform this work with the least possible drop of pressure as measured between the flue sheet 9 30 and the stack proper 3. It is further to be noted that when the front end door 6 is open every part within the smoke box is immediately opened to view and is easy of access for inspection or repair. There are no plates, diaphragms, nettings or the like, which must first be removed.

Attention is called to the nozzle N. It does not extend above the floor 17 and therefore never interferes with the placement or with the removal of the whirl-promoting tuyère.

40 By preference the parts 14 and 16 are metal castings and the numerous tangential blades

which connect them have their ends embedded in said castings in the foundry process of forming them. All parts are of great durability and cost little to repair or to replace.

Attention is called to the fact that the invention is not necessarily limited to embedding the bowl C' in cement. An all metal structure may be used, omitting the cement, but it is desirable to prevent the lodgment of burning cinders in the lower part of a smoke box and the filling of 10 cement accomplishes this purpose by occupying the spaces surrounding the metal bowl C'. And as before pointed out, the floor 17, which the cement forms, serves as a cinder deflector and a guiding part which ensures the passage of all 15 cinders into and through the whirl-promoting element 15.

Having thus described my invention, I claim as new and desire to secure by Letters Patent:

1. A locomotive front-end or smoke box, its 20 inside stack and coaxial exhaust nozzle, the latter positioned in the bottom of the smoke box, in combination with a bowl portion larger than said stack and fixed in position surrounding said nozzle, and, a whirl-promoting tuyère positioned and 25 forming a direct connection between the top of said bowl and the lower end of said inside stack.

2. A locomotive front-end or smoke box, its inside stack and coaxial exhaust nozzle, the latter positioned in the bottom of the smoke box, in 30 combination with a bowl portion larger than said stack and fixed in position surrounding said nozzle, a whirl-promoting tuyère positioned between the top of said bowl and the lower end of said inside stack, said bowl portion being formed 35 within a body of cement which is laid in the bottom of the smoke box and which presents a cinder deflecting floor surrounding the base of said tuyère.

CHARLES GILBERT HAWLEY. 40
